UNITED STATES PATENT OFFICE

KARL SIEG, OF PHILADELPHIA, PENNSYLVANIA, ASSIGNOR TO SAMUEL M. LANGSTON
CO., OF CAMDEN, NEW JERSEY, A CORPORATION OF NEW JERSEY

DRUM WINDER

Application filed August 26, 1931. Serial No. 559,445.

This invention relates to winding machines of the type in which paper or other material in web or sheet form is wound on a roll supported by a pair of parallel driven drums and 5 pressed down by a superposed driven roller.

In many instances, sheet material, either in the manufacture or by subsequent step or steps, is produced with one surface of different character than the opposite surface. In 10 the winding of such material, it is sometimes desired to have one surface facing outwardly, and in other instances it is desired to have said surface facing inwardly on the roll.

The main object of the present invention 15 is to provide mechanism whereby the material going to the machine with a given surface uppermost, may be wound with said surface facing either inwardly or outwardly on the roll.

20 In the ordinary drum winder, it is customary to rotate the drum which brings the paper on to the roll, at a slightly lower speed than the second drum in order that the proper tension may be put on the material and the 25 roll will be hard and solid without maintaining high tension on the material as delivered to the machine.

A further object of the present invention 30 is to provide simple means whereby the relative speeds of the two roll supporting drums are automatically varied in accordance with the direction of rotation thereof, whereby the second drum with which the material comes 35 in contact will rotate faster than the first drum, irrespective of whether the material be delivered to one drum for winding the sheet with one surface outermost, or to the other drum for winding the sheet with the said surface innermost.

40 A further object of the invention is to provide simple mechanism for reversing the direction of the drums without reversing the direction of the slitting or edge trimming mechanism, or the direction of feed of the 45 sheet through said mechanism.

In the accompanying drawings, there are shown for the purpose of illustration, two forms of the present invention, and in which

50 Fig. 1 is a front elevation of the machine partly in section.

Fig. 2 is a section taken on line 2-2 of Fig. 1, certain of the parts being shown somewhat diagrammatically.

Fig. 3 is a section taken on line 3-3 of Fig. 1. 55

Fig. 4 shows one of the gears associated with one of the winding drums, and having a unidirectional clutch for driving it.

Fig. 5 is a section taken on line 5-5 of Fig. 4, and 60

Fig. 6 is a view showing another form of gearing for reversing the winding drums.

Although the invention is illustrated in a type of machine particularly adapted for the winding of paper, it should be understood that it is also applicable to the winding of any suitable web material. Therefore, although for the sake of conciseness I will hereinafter refer only to paper as the material being operated on, it is to be understood that 65 by the term "paper" I include any suitable web material which may be used in any type of machine embodying the invention. 70

The invention is shown as applied to a machine of the general type disclosed in the 75 Langston Patent 1,488,126. In this type of machine, the paper is drawn from a paper making machine or any other suitable source, slit into sections, and trimmed at the edges and wound. The machine illustrated has a pair of end frames 10 connected together by a base 11 and by suitable cross-braces, one of which is shown as an I-beam 12.

The paper A is fed over an idler 13, under 80 a second idler 14, and through a suitable slitting mechanism which, in the form shown, includes a driven shaft 15 having shear cutters 16 mounted thereon, and a series of co-acting cutters 20, each mounted on a shaft or rod 17 carried by a bracket or carrier 18 adjustable endwise to vary the overlap of the cutters, and mounted on a stationary shaft 19. 85

The cutters 16 and 20 together with the brackets or carriers 18 may be adjusted lengthwise of their respective shafts 15 and 19 to any desired position in accordance with the desired width of slotted strips, and the width of the sheet, and the cutters 20 may be swung into and out of engagement with the paper by loosening and turning the brack- 95 100

ets or carriers on the shaft 19. This general type of slitting mechanism may be adapted for slitting paper into sections, or it may be used merely to trim the side edges of the paper. This particular type of slitting mechanism forms no part of the present invention, but is merely described as constituting a part of a machine in which the present invention may be used to advantage.

10 The paper after passing through the slitting mechanism, passes in contact with an idler 21 and then in contact with one of a pair of positively driven winding drums 22 and 23. The paper A is threaded to follow the course indicated at A' or A'' in accordance with the direction of rotation of the drums, and the surface of the paper which is to be outermost on the roll. The paper is then wound on a mandrel 24 to form a roll C. This mandrel 24 has a vertically guided movement in a plane between the two winding drums 22 and 23, and this movement may be facilitated by counterbalancing members more fully shown and described in the Langston patent above referred to.

15 Above the roll of paper C is a pressure or riding roller 25 which has a vertically guided movement, and which is positively rotated, for instance, by the mechanism also shown in the Langston patent above referred to. In a machine of this type, the rollers 22 and 23 are positively rotated, the roll which first engages the paper as it is applied to the roll, being so geared as to have a lower peripheral speed than the second winding drum, in order that the proper tension and pressure rubbing action may be put on the material, and the roll be tightly formed without maintaining high tension on the paper as it is delivered 20 to the machine.

25 So far as the main operation and relative positions of the parts so far described are concerned, these are well known in the art.

30 All of the positively driven elements so far described are driven by a common drive. Therefore, if it is desired to change the direction of winding of the paper, the mere reversal of the drive in an ordinary machine would not serve to automatically vary the 35 relative speed of the two winding drums in accordance with the change in direction of the paper. Furthermore, this reversal of the drive will cause the reversal of the slitting mechanism, which may be of a type which 40 will only operate in one direction.

45 As an important feature of the present invention, means are provided whereby the direction of rotation of the drums may be reversed, and whereby the relative speeds of the two winding drums 22 and 23 are automatically varied in accordance with the direction of rotation thereof, so that the second winding drum with which the sheet of paper comes in contact will always rotate faster 50 than the first winding member, irrespective

of the direction of feed of the material to the roll.

55 In the form illustrated, there are employed a pair of bearing posts 31 and 32 mounted at one side of the machine, and having journaled therebetween a drive shaft 33 which may have mounted thereon a suitable drive pulley 34. A clutch 35 is provided for starting and stopping the machine, and has its driving member keyed on the shaft 33, and its driven member loose thereon.

60 A gear 46 is provided for meshing with and driving gears connected to both drums to rotate them in the same direction, and between this gear 46 and the driven member of the clutch, there is provided driving gearing of such a character that the gear 46 may be driven in forward or reverse direction in respect to the direction of rotation of the shaft 33. In the specific form of gearing 65 illustrated, there is provided a shaft 38 journaled between the frame structure of the machine and the bearing post 32. This shaft 38 may be connected and drive the cutter shaft 15, and may be driven by a gear 36 70 secured to the driven member of the clutch, and a gear 37 secured to the shaft 38.

75 For driving the gear 46 from the shaft 33, there is provided a shaft 30 in alignment with the shaft 33, and the gear 46, and journaled in the bearing post 32. On this shaft 30 are a gear 40 and a bevel gear 41. The latter meshes with a bevel gear 42 mounted on a shaft 43 journaled in a pair of bearing posts 44. Aligned with the bevel gear 41 and meshing with the bevel gear 42 is a bevel gear 45 connected to the gear 46 which has the same diameter as the gear 40, and which is aligned therewith.

80 The shaft 38 carries a gear 47 which is splined thereon to permit said gear to be shifted from a position in which it meshes with the gear 40 to a position where it meshes with the wide gear 46. The axial position of the gear 47 thus determines the direction 85 of rotation of the wide gear 46. With the gear 47 meshing with the gear 40, the gear 46 will be rotated in one direction, and with the gear 47 meshing with the gear 46, the latter will be driven in the opposite direction.

90 Various other types of forward or reverse driving gearing may be employed. For instance, the shafts 38 and 30 and gears 36, 37, 40 and 47 may be omitted, and a shaft 95 connected to the driven member of the clutch, extended through the bevel gear 41 to support it. Between the two bevel gears 41 and 45, a double acting jaw clutch might 100 be employed to either lock the gear 41 to the clutch driven shaft, and release the gear 45 therefrom, or to lock the clutch driven shaft to the gear 45 and free the gear 41. Other means would be employed for driving 105

the cutter shaft if the cutters be of the driven type.

The winding drum 22 has a shaft 48 extending beyond one of the side frame members 10, and having keyed thereto a sleeve

49. Loosely mounted on this sleeve 49 are a pair of gears 50 and 51 both meshing with the wide gear 46, and having separate and opposite unidirectional clutch connections with said sleeve 49. These unidirectional

clutch connections are so arranged that one of these gears while rotating in one direction, will drive the sleeve 49, while the other gear rotating in the same direction idles around said sleeve 49. The winding

drum 23 is similarly provided with a shaft 52 which is keyed to a sleeve 53 carrying a pair of gears 54 and 55 transversely aligned with the gears 50 and 51 respectively, and having separate unidirectional clutch en-

gagements with said sleeve, and also meshing with the gears 46. These gears 54 and 55 are coupled to the sleeve 53 to provide driving connections with said sleeve in opposite directions.

One gear of the pair 50 and 51, and one gear of the pair 54 and 55 have one or two teeth more than the other gear of the same pair, but this difference does not affect their mutual engagement with the gear 46.

For instance, one gear of each pair may have thirty teeth, and the other gear of the same pair may have twenty-nine teeth. Furthermore, the two gears (one of each pair) which have the same direction of drive, have different numbers of teeth. Thus, when the gear 46 is rotated in one direction, one gear of each pair will drive its corresponding winding drum, and one drum will go slightly faster than the other, and when the gear 46 is rotated in the opposite direction, the other gear of each pair will act as a drum driver, and the last mentioned drum will go the faster.

The unidirectional clutch connection for the two pairs of gears associated with the winding drums may be of any suitable type, and in the form shown comprise rollers 60 mounted in slots 61 formed in the inner periphery of these gears. These slots 61 have an enlarged portion at 62 for loosely receiving these rollers, and a smaller portion at 63 where the rollers will be jammed between the gears and the sleeve 49, so that said sleeve will be driven thereby. The rollers 60 are urged against the smaller sections of the slots 61 by springs 64 disposed in recesses 65 in the gear. A unidirectional clutch for driving rotation in the opposite direction would be similar to that shown, but would have the slots 61 extending in the opposite direction, and the position of the springs 64 correspondingly reversed.

In the operation of the machine, the gear

either the gear 40 or the gear 46 according to the desired direction of feed of the paper to the drums. When the gear 47 is in mesh with the gear 40 as shown in Fig. 1, the power is transmitted from the drive shaft 33 to the gears 36 and 37, through the shaft 38 to the gear 47, and then to the gear 40, bevel gears 41, 42 and 45, gear 46, and one gear of each of the two pairs of gears associated with the winding drums 22 and 23 to drive both drums, but one slightly faster than the other.

By shifting the gear 47 to the dotted position to mesh with the gear 46, the direction of the gear 46 will be reversed, this reverse rotation serving to select a different pair of gears on the shafts of the winding drums for driving these drums, the selected gears automatically varying the relative speeds of the winding drums, so that the second drum with which the material comes in contact will rotate faster than the first drum.

The pressure roller 25 will be driven from the gear 46 by any suitable manner, so that the reversal of rotation of said gear will cause a corresponding reversal of rotation of said pressure roller 25.

Having thus described my invention, what I claim as new and desire to secure by Letters Patent is:—

1. A paper winding machine including a pair of winding drums adapted to support the roll of paper being formed, means for rotating said drums in the same direction at different speeds but at a fixed ratio, means for reversing the direction of rotation of the drums, and means for reversing the relative speeds of said drums upon reversal of the direction of rotation.

2. A winding machine including a pair of winding drums adapted to support the roll being formed, a direction reversible gearing, and means between said gearing and said winding drums for rotating said drums at different speeds in the same direction when said gearing is driving in one direction, and for reversing the relative speeds of said drums when said gearing is driving in the opposite direction.

3. A winding machine including a pair of winding drums adapted to support the roll being formed, means for rotating said winding drum in one direction with one drum at a faster speed than the other, and means for reversing the direction of rotation of said drums and automatically reversing their relative speeds.

4. A paper winding machine including a winding shaft on which paper may be wound, a pair of winding drums adapted to contact with the outer periphery of the roll of paper being formed, a pair of coaxial gears of approximately the same pitch diameter, a gearing for continuously rotating one gear from the other and in the opposite direction, a drive shaft, a gear

mounted for rotation with said shaft but slidable therealong into mesh with one or the other of said pair of coaxial gears, and means for rotating said drums from one of said coaxial gears.

5. A paper winding machine including a pair of winding drums adapted to contact with the outer periphery of the roll of paper being formed, a pair of coaxial gears, a gearing connection for rotating one gear from the other, and in the opposite direction, a drive shaft, a gear mounted for rotation with said shaft but slidable therealong, said last mentioned gear being adapted to mesh with one or the other of said pair of coaxial gears, and means driven by one of said gears for rotating said drums at different speeds in the same direction when said third gear meshes with one of said pair of gears, and for reversing the relative speeds of said drums when said third gear meshes with the other of said pair of gears.

6. A paper winding machine including a pair of winding drums adapted to support the roll of paper being formed, a drive gear, a pair of coaxial gears having a slightly different number of teeth meshing with said drive gear, and having opposite unidirectional drive connections with one of said drums for rotating said drum at one speed when rotating in one direction, and at a different speed when rotating in the opposite direction.

7. A paper winding machine including a pair of winding drums adapted to support the roll of paper being formed, a drive gear, a pair of gears mounted on each of said winding drums, the two gears of each pair having a different number of teeth, all of said gears meshing with said drive gear, means for automatically effecting a driving connection between one gear of each pair and its corresponding drum when said drive gear is rotated in one direction, and means for automatically effecting a driving connection between the other gear of each pair and its associated winding drums when said drive gear is rotated in the opposite direction.

8. A paper winding machine including a pair of winding drums adapted to support the roll of paper being formed, a reversible gear, a pair of gears mounted on each of said winding drums, all of said gears meshing with said reversible gear, and means including unidirectional clutches between said gears and said winding drums for automatically effecting a driving connection between one gear of each pair and said drums, for rotating both drums in one direction, and for automatically disconnecting said last mentioned gears from driving connection with their associated winding drums, and for automatically effecting a driving connection between the other gears and their associated drums for the rotation of said winding

drums in the opposite direction when said reversible gear is reversed.

9. A paper winding machine including a pair of winding drums adapted to support the roll of paper being formed, a reversible gear, a pair of gears mounted on each of said winding drums, the gears of each pair having a different number of teeth, one of the gears of one pair being similar to one of the gears of the other pair, and the other gear of the said one pair being similar to the other gear of the said other pair, all of said gears meshing with said reversible gear, means for automatically effecting a driving connection between two different toothed gears of both pairs and said drums for rotating said drums in one direction, and for automatically disconnecting said last mentioned gears, and for automatically effecting the driving connection between the other gears and their associated winding drums in the opposite direction when said reversible gear is reversed.

10. A paper winding machine including a pair of winding drums adapted to contact with the roll of paper being formed, a reversible gear, a pair of gears mounted on each of said winding drums, the gears of each pair having a different number of teeth, one of the gears of one pair being similar to one of the gears of the other pair, and the other gear of the said one pair being similar to the other gear of the said other pair, and a unidirectional clutch between each of said gears and its corresponding winding drum, and clutches associated with the similar gears of both pairs having oppositely driving connections with their associated winding drums.

11. A paper winding machine including a pair of winding drums adapted to rotate the roll being formed, a reversible gear, a driving connection between said reversible gear and said drive shaft, a pair of gears mounted on each of said winding drums, the gears of each pair having a different number of teeth, one of the gears of one pair being similar to one of the gears of the other pair, and the other gear of the said one pair being similar to the other gear of the said other pair, all of said gears meshing with said reversible gear, means for reversing the rotation of said reversible gear, and means for automatically effecting a driving connection between two different toothed gears of said pairs and their respective drums for rotating said winding drums in one direction, and for automatically effecting a driving connection between the other gears and their associated winding drums for rotating said drums in the opposite direction when the direction of rotation of said reversible gear is reversed.

12. A paper winding machine including a pair of winding drums adapted to support the roll of paper being formed, a drive shaft, means for driving both of said drums in either direction with respect to said drive

- shaft, but with one drum at a higher surface speed than the other, and means for reversing the relative speeds of said drums upon reversing the direction of rotation thereof. 13. A paper winding machine including a pair of winding drums adapted to support the roll of paper being formed, a drive shaft, and means for driving both drums in either direction with respect to said drive shaft, but with one drum at a faster surface speed than the other when rotating in one direction, and with the reverse speed ratio when rotating in the opposite direction. 14. A paper winding machine including a pair of winding drums adapted to support the roll of paper being formed, a one way rotating gear, means for rotating said drums in one direction at different speeds but at a fixed speed ratio from said gear, means for rotating said drum in the opposite direction from said gear, and means for reversing the relative speeds of said drums upon reversing the direction of rotation of said drums. 15. A web winding machine including a pair of winding drums adapted to engage the roll of material being formed, each drum having a pair of gears, one free to rotate in one direction in respect to the drum and the other free to rotate in the other direction in respect to the drum, and a driving gear meshing with both gears of both pairs. 16. A web winding machine including a pair of winding drums adapted to engage the roll of material being formed, each drum having a pair of gears, one free to rotate in one direction in respect to the drum and the other free to rotate in the other direction in respect to the drum, and a driving gear meshing with both gears of both pairs, and one gear of each pair having a slightly larger number of teeth than the other gear of the same pair. 17. A web winding machine including a pair of winding drums adapted to support the roll of material being formed, a pair of gears associated with said drums and of different gear ratio, for driving said drums at different speeds in one direction, and a second pair of gears associated with said drums and of different but opposite gear ratio, for driving said drums in the other direction. 18. A web winding machine including a front drum and a rear drum, said drums being adapted to support the roll of material being formed, means for driving said drums in one direction with the front drum rotating at a higher peripheral speed than the rear drum, and means for driving the drums in the reverse direction with the front drum at lower peripheral speed than the rear drum. 19. A paper winding machine including a pair of winding drums adapted to support the roll of material being formed, a drive shaft, means for rotating both drums in one direction with respect to said drive shaft and at different fixed relative speeds, and means for driving said drums in the opposite direction and reversing their relative speeds. 20. A web winding machine including a cutter shaft, a clutch for stopping and starting said shaft at will, a pair of winding drums for engaging the roll of material being wound, and reversing gears between said drums and said cutter shaft for rotating said drums in either direction in respect to said cutter shaft. 21. A winding machine including a pair of parallel winding drums adapted to support the roll of material being wound, a rotary member engaging the material in its path of movement to one of said drums, a one-way rotating drive shaft, means between said shaft and said rotary member for rotating said member in one direction only, and means between said drive shaft and said drums for rotating said drums in either direction in respect to said member. Signed at Camden in the county of Camden and State of New Jersey this 18th day of August A. D. 1931.
